UNITED STATES PATENT OFFICE.

FRANK J. THOMPSON, OF LOS ANGELES, CALIFORNIA.

SHADE-EDGE-HOLDING DEVICE.

No. 878,690.

Specification of Letters Patent.

Patented Feb. 11, 1908.

Application filed February 11, 1907. Serial No. 356,731.

To all whom it may concern:

Be it known that I, FRANK J. THOMPSON, a citizen of the United States, residing at Los Angeles, in the county of Los Angeles and 5 State of California, have invented new and useful Improvements in Shade-Edge-Holding Devices, of which the following is a specification.

My invention relates to a shade edge holder 10 which is adapted to hold the shade close to the window; and it is the prime object thereof to provide a device which will hold the edges of the shade against the window sash, thereby eliminating any disturbance of the 15 shade by wind and preventing any view through the window when the shade is drawn.

A further object is to provide a device 20 which may be easily changed from its operative position against the shade to its inoperative position away from the shade.

A further object is to provide a device which may be easily attached to any window frame.

A further object is to provide a device which is slighty and elegant in appearance.

I accomplish these objects by means of the device described herein and illustrated in the accompanying drawings, in which:—

30 Figure 1 is an inside elevation of a window provided with my shade holders. Fig. 2 is a full size elevation of a shade holder. Fig. 3 is a section of the locking plate on line 3—3 of Fig. 2, showing the holder in its locked position. Fig. 4 is a perspective of the locking key. Fig. 5 is a perspective of the locking plate and a portion of the shade holding rod in its locked position.

Referring to the drawings, 1 is a window 40 frame provided with a shade 2. Shade edge holders 3 are provided on each of the upright panels of the window frame, and hold the edges of the shade against the window frame 4 as will be hereinafter described.

45 Shade edge holders 3 consist of shade holding rods 5 which are bent to the configuration shown in Figs. 1 and 2. The tops and bottoms are bent at right angles and are relatively supported by bearings 6. At a 50 convenient distance from the bottom of the window frame, rods 5 are bent into a U, 5^a, and pass through locking plates 7. Locking plate 7 consists of a box-shaped body 8 secured to the window frame by screws. A 55 key 9 is mounted in the locking plate, having

on its lower end a locking key 10 having wedge-shaped ends which are adapted to swing over the shade holding rod where the rod is bent to a U-shape, as shown in Figs. 2 and 5. Body 8 of the locking plate is cut 60 away as at 11 to admit of the turning of key 10. Rod 5 passes through holes 12 in the locking plate body, and slots 13 from these holes provide a means for inserting and removing the rod.

65 When the device is in the position shown in Figs. 1 and 2, rod 5 projects in over the edge of the window frame and over the edge of the shade, the locking key holding the rod in position when it is desired to remove 70 the rod from engagement with the curtain. Key 9 is turned slightly, thereby releasing the rod, and it may then be turned in bearings 6 away from the shade.

75 I have shown holes 12 out of line with bearings 6, and U 5^a shorter than the right angled arms at the ends of rods 5, so that when the rod is turned to any position other than the one shown, it will be distorted and have a tendency to return to that position. 80

85 From the foregoing description it will be seen that I have provided a shade edge holder which may be attached to any ordinary window and will provide an absolute means for holding the shade flat against the window frames and will prevent any movement of the shade by wind when the window is open behind it. On account of this last, I am enabled to open the windows and still keep the shade down, which is a condition 90 most highly desired.

Having described my invention, what I claim as new and desire to secure by Letters Patent is:—

95 1. In a shade edge holder, a rod extending vertically along the shade near its edge, said rod being secured to the window casing, and means to secure said rod in its position against the shade.

100 2. In a shade edge holder adapted to be attached to a window frame, a vertical rod pivotally attached to the window frame and adapted to swing over the edge of the shade, and means to hold said rod in its position over the edge of the shade.

105 3. In a shade edge holder adapted to be attached to a window frame, a vertical rod provided with ends bent horizontally, said horizontal ends being pivotally attached to the window frame, said rod also being pro- 110

vided with a centrally located horizontal U-shaped portion, and a lock adapted to swing over said U-shaped portion of the rod.

4. In a shade edge holder adapted to be attached to a window frame; a vertical rod provided with ends bent horizontally, said horizontal ends being pivotally attached to the window frame, said rod also being provided with a central horizontal U-shaped portion; and a lock adapted to wedge said

U-shaped portion flatly against the window casing.

In witness that I claim the foregoing I have hereunto subscribed my name this 4th day of February, 1907.

FRANK J. THOMPSON.
